UNITED STATES PATENT OFFICE.

AUGUST KOENIG, OF LOWELL, MASSACHUSETTS, ASSIGNOR TO THE LAMSON COMPANY, OF BOSTON, MASSACHUSETTS, A CORPORATION OF NEW JERSEY.

CARRIER DESPATCH SYSTEM.

1,373,080.

Specification of Letters Patent. Patented Mar. 29, 1921.

Application filed December 27, 1919. Serial No. 347,828.

To all whom it may concern:

Be it known that I, AUGUST KOENIG, a citizen of the United States, and resident of Lowell, in the county of Middlesex and 5 State of Massachusetts, have invented new and useful Improvements in Carrier Despatch Systems, of which the following is a specification.

This invention relates to carrier despatch systems of the type where carriers are moved 10 along tracks.

One of the objects of the present invention is to provide simple and efficient means whereby carriers delivered at a station may 15 be automatically divided and mechanically placed on separate receiving racks. It is another object of the invention to provide such means separate and distinct from any means utilized for separating the carriers 20 and directing them to different stations.

It is a further object of the invention to provide simple and efficient switch and switch operating means in connection with the class separating means upon the carriers. 25

Other and further objects and results of the invention will appear as the disclosure proceeds.

The invention is adapted for use in connection with the usual despatch systems of 30 the track type using cable motive power, with but slight modification of certain of the carriers and of the track at the central or cashier's station.

In general, in systems of this type, each 35 carrier travels between a certain sub-station and the cashier's station. Selective means at each station are provided to coöperate with lugs on the sides of the carriers to stop the carrier at its own sub-station. All carriers, however, are stopped at a single cashier's station.

It is the purpose of the present invention to provide separate receiving extensions at the central station and selective means so 45 operating that certain predetermined carriers may come to rest on one extension and the remainder on another extension.

This is of particular utility in separating cash sales sent in for change, from credit 50 sales sent in for approval, so that they may be expeditiously handled by different clerks in the central station.

I have shown a preferred embodiment of my invention in the accompanying drawings, in which—

Figure 1 is a perspective view of a carrier provided with my improved class determining means in connection with a broken away portion of the track and guide means;

Fig. 2 is a face view of a double receiving 60 terminal;

Fig. 3 is an enlarged perspective view of a portion of Fig. 2; and

Fig. 4 is a view of a portion of Fig. 2 as seen from the right side. 65

The carrier 5 is of the usual type with a door 6, door latch 7 on the face thereof, a bearing member 8 and guide lugs 9. It carries the usual lugs 10 for the purpose of effecting delivery to a predetermined station 70 in the well-known manner old in the art and not a part of the present invention. The carrier rides upon rails 11 which pass between the bearing member 8 and guide lugs 9.

A movable cable and gripping means on 75 the carrier (not shown) are provided to move the carrier in the manner well-known in the art.

The track 11 has attached thereto the movable switch 12 which, as shown in Fig. 80 2, is normally held by the spring 14 in alignment with receiving extension 13. This spring 14 has one end attached to the guide member 15 and the other end to the guide bar 16 by the pin 17. The guide 85 member 15 is supported on the track frame by the vertical brace 18. The track members of the switch are pivoted by pins 19 to arms 20 which are rigidly connected to the guide bar 16. The guide bar 16 90 passes through slotted openings 21 in the in-turned ends of the guide member 15.

Extending in the opposite direction from the receiving extension 13 is a similar receiving extension 22. 95

Attached to the track frame is the selector guide 23 adapted to contact with the selector guide lug 24, which extends from the face of the carrier, in the manner shown in Fig. 1.

In the operation of the device the carrier 100 will come down the track 11 from the top as seen in Figs. 2 and 4. If it has no lug 24 it will normally pass along the switch 12 in its position, as shown, and come to rest upon the receiving extension 13. If, however, the 105 carrier is fitted with a lug 24, this lug will pass to the right of the nose 25 on the selector guide 23 and as that guide curves to the right the switch member 12 will be swung to the right against the tension of the spring 110

14 until the switch is in alignment with receiving extension 22 and the carrier will pass on to that extension. When the carrier leaves the switch the tension of the spring 14 returns it to its normal position as seen in Fig. 2.

The strength of the spring 14 is sufficient to maintain the switch in its normal position against the thrust due to the inertia of a carrier striking the switch and passing to receiving extension 13.

The portion of track 11' is used in sending carriers away from the station and forms no part of the present invention.

I am aware that efforts have been previously made to provide means for separating carriers at a central station by means of selective devices operating through lugs on the sides of the carrier in a manner similar to the method of selective delivery to stations on the return from the central station.

In such a device there is a limited space on the sides of the carrier which may be utilized for selective lugs and where a portion

of such surface must be given over to lugs to determine selective delivery at the central stations, it is not possible to have the usual number of substations on the line. This necessitates the use of more lines with a consequent increase in expense.

With the present invention no sub-stations need be eliminated. This makes it possible to add the new selective device at the central station to existing lines with little expense.

All that is necessary is the change of track ends at the central station and the addition of new carriers having class determining lugs. Moreover, the class determining lug being on a different side, the two classes of carriers are more readily distinguished and there is consequently less likelihood of use of an incorrect carrier at a sub-station.

A further and important advantage obtained by placing the class determining lug upon the face of the carrier consists in the fact that in this case the two delivery extensions may be placed in the same plane. This results in a very considerable saving in desk space at the central station. It also makes all portions of the track more accessible.

An additional advantage of the laterally operating switch consists in there being less likelihood of a carrier jumping the track at the moving end of the switch. In a lift switch, which raises the carrier from one track to another in the direction of its face, the transfer from switch to track end is made with only the narrow lug 9 holding the carrier to the switch. The thickness of this lug can easily pass between switch point and track end if the adjustment between them is not close. On the other hand in the present laterally operating switch, should the switch point and track end be not in

exact alignment the curved ends of the carriers will tend to guide the yielding switch into alignment and the carrier does not leave the switch until a considerable portion is already between the track.

70

I claim:—

1. A carrier system comprising a track, carriers adapted to travel along said track, a central station and a plurality of substations, station selector means upon certain faces of the carriers adapted to coöperate with means at the several sub-stations to deliver each carrier at a predetermined station, class determining means on certain of said carriers, upon another face than the faces containing the station selector means, a plurality of delivery extensions at said central station, and selective delivery means at said central station adapted to cause the carriers provided with class determining means to be placed on one of said delivery extensions, and to cause the other carriers to be placed upon a different delivery extension.

2. A carrier system comprising a track, carriers adapted to travel along said track, a central station and a plurality of substations, station selector means upon the sides of the carriers adapted to coöperate with means at the several sub-stations to deliver each carrier at a predetermined station, class determining means on certain of said carriers upon the faces thereof, a plurality of delivery extensions at said central station, and selective delivery means at said central station adapted to cause the carriers provided with class determining means to be placed on one of said delivery extensions, and to cause the other carriers to be placed upon a different delivery extension.

95

3. A carrier system comprising a track, carriers adapted to travel along said track, certain of said carriers having class determining means upon the faces thereof, a central station to which said carriers are delivered, a plurality of delivery extensions at said station, a switch at said station adapted normally to place said carriers on one of said delivery extensions, selector means co-operating with the class determining means on the carriers to cause carriers provided with said class determining means to be placed by said switch on another of said delivery extensions.

100

4. A carrier system comprising a track, carriers adapted to travel along said track, certain of said carriers having class determining means upon the faces thereof, a central station to which said carriers are delivered, a plurality of delivery extensions at said station, a switch at said station adapted normally to place said carriers on one of said delivery extensions, selector means co-operating with the class determining means on the carriers to cause carriers provided

with said class determining means to be placed by said switch on another of said delivery extensions, the portions of both said extensions adjacent the switch being in the same plane.

5. A carrier system comprising a track, carriers adapted to travel along said track, a central station, station selector means upon the lateral surfaces of the carriers adapted 10 to coöperate with means at several sub-stations to deliver each carrier at a pre-determined sub-station, class determining means upon the face of certain of said car-

riers, two delivery extensions at the central station, a yielding switch normally connecting the main line and one of said stations, a guide member adjacent said switch adapted to coöperate with the class determining means on the carriers to move the switch laterally and cause carriers fitted with said 15 class determining means to be passed by the switch to the other of said delivery extensions.

Signed by me at Boston, Massachusetts this 23rd day of December 1919.

AUGUST KOENIG.
